UNITED STATES PATENT OFFICE.

JOHN H. REES, OF MERIDEN, CONNECTICUT, ASSIGNOR TO FRED REES AND WILLIAM W. MORRELL, BOTH OF MERIDEN, CONNECTICUT.

REEL FOR MOVING-PICTURE FILMS.

1,089,082.

Specification of Letters Patent.

Patented Mar. 3, 1914.

Application filed November 17, 1913. Serial No. 801,460.

To all whom it may concern:

Be it known that I, JOHN H. REES, a citizen of the United States, residing at Meriden, in the county of New Haven and State of Connecticut, have invented a new and useful Improvement in Reels for Moving-Picture Films; and I do hereby declare the following, when taken in connection with the accompanying drawings and the characters 10 of reference marked thereon, to be a full, clear, and exact description of the same, and which said drawings constitute part of this application, and represent, in—

Figure 1 a side view of a reel for moving picture films constructed in accordance with my invention. Fig. 2 a sectional view of the hub with the clamping finger in the open position. Fig. 3 a similar view with the clamping-finger in the closed position 20 and engaged with the end of a moving picture film. Fig. 4 a plan view illustrating a film engaged with the hub and having the disks broken away. Fig. 5 a plan view of the hub with the spring-plate and clamping-finger removed, showing the recess with the bearing-plate in the bottom thereof.

This invention relates to an improvement in reels for moving picture films. As the films are drawn through the kinematograph, 30 it is wound upon a reel; and in the usual construction of these reels difficulty is experienced in connecting the end of the film with the reel so that as the reel is revolved the film will be wound.

The object of this invention is to provide 35 a reel with which the film may be readily engaged or disengaged; and the invention consists in the construction hereinafter described and particularly recited in the claims.

As usually constructed these reels consist 40 of a central hub 2 with disks 3, 4, at opposite ends, these disks being usually provided with holes or openings 5 through which the fingers may be passed for connecting the 45 film with the hub. As a convenient means for connecting the end of the film with the hub, I form the hub with a recess 6 at one end of a shallow groove 7, and in the bottom of the recess I secure a plate 8 formed 50 on opposite sides with outwardly projecting ribs 9 and 10 for the purpose as will hereafter appear. Extending through the groove 7 and secured by a screw 11 is a plate 12 formed at its outer end which extends 55 into the recess 6 with ears 13 and 14 be-

tween which is pivoted a clamping finger 15 the outer end of which is adapted to bear upon the surface of the hub and its inner end 16 rests upon the plate 8 in the recess. I may here note that the plate 12 is formed 60 from spring metal so as to normally force its outer end into the recess and clamp the finger 15 against the hub. The ribs 9 and 10 provide a bearing for the inner end 16 of the clamping finger, and these ribs are 65 formed with stop-shoulders 17 and 18 which limit the upward movement of the clamping-finger. When ready for use the clamping-finger 15 is raised as shown in Fig. 2 70 of the drawings, and one end of a film 19 is placed upon the hub beneath the finger which is then snapped downward, ready access being had to it through one of the finger-openings 5. When snapped down the pressure of the plate 12 will firmly hold 75 the clamping-finger against the hub so as to firmly grip the film between them, and owing to the location of the pivot with relation to the inner end of the clamping-finger, the clamping-finger will remain in its open position when desired.

I claim:—

1. A reel for moving picture films comprising a hub and two end disks, said hub formed with a recess, a spring plate connected with the hub and extending into said recess, and a clamping finger pivoted to the end of the spring-plate and adapted to be held thereby in close engagement with the surface of the hub.

2. A reel for moving picture films comprising a hub and two disks, said hub formed with a recess and a groove opening into the same, a spring-plate seated in said groove and formed at its end with ears which extend into said recess, a spring-finger pivotally connected with said ears and formed with an inwardly turned end having a bearing within said recess.

3. A reel for moving picture films comprising a hub and two disks, said hub formed with a recess, a bearing-plate in the bottom of said recess, a spring-plate secured to said hub and formed at its inner end with ears projecting into said recess, and a clamping-finger pivotally connected with said ears and having its inner end extended into contact with said bearing-plate.

4. A reel for moving picture films comprising a hub and two disks, said hub formed

2
with a recess, a plate in the bottom of said recess, said plate formed with bearing ribs, a spring-plate secured to said hub and formed at its ends with ears projecting into said recess, and a clamping-finger pivoted to said spring-plate and formed at its inner end with a bend adapted to bear upon the ribs of said bearing-plate.

5. A reel for moving picture films comprising a hub and two disks connected therewith, said hub formed with a recess, a plate in the bottom of said recess, a groove extending into said recess, a spring plate se-

cured in said groove and formed at its end with ears projecting into said recess, and a clamping-finger pivoted to said spring plate and formed at its inner end with a bend having a bearing upon said bearing plate.

15 In testimony whereof, I have signed this specification in the presence of two subscribing witnesses.

JOHN H. REES.
